UNITED STATES PATENT OFFICE.

HALVER R. STRAIGHT, OF ADEL, IOWA.

GRANULATOR BLADE.

Application filed June 9, 1920. Serial No. 387,765.

To all whom it may concern:

Be it known that I, HALVER R. STRAIGHT, a citizen of the United States, residing at Adel, in the county of Dallas, State of Iowa, have invented a Granulator Blade, of which the following is the specification.

This device relates to improvements in devices for granulating semi-substances such as clay, or shale, and pertains particularly to that class of machines having a rotary shaft provided with a series of saggard and radial blades designed to rotate in a suitable trough.

But blades of this kind have caused considerable trouble due to the fact that the forward edge of the blades wear round at the periphery, this causes the blades to pinch the material to be granulated, between the said rounded edge and the wall of the container trough.

This pinching causes a considerable unnecessary power to drive the granulator besides producing unsatisfactory results.

It is the object of my invention to provide improvements in the blades for granulators and particularly to provide means whereby the cutting points will remain comparatively sharp, also, new and improved means of mounting the blade and reinforcing the same.

Referring to the accompanying drawings:

Fig. 1 is a transverse sectional view of a container and showing my improved blade mounted on a suitable shaft.

Fig. 2 is segmental top view of the same.

Fig. 3 is a detail end elevation of one of my improved blades.

Referring to the drawings, the reference numeral 10 indicates the trough or retainer to be used in connection with my improved granulator device and is designed to have rotatively mounted, a longitudinal shaft 11. This shaft 11 is provided with a series of equal distant holes 12 passing transversely through it. The shaft may be rotated by any suitable power. The manner of mounting this shaft and rotating it form no part of my present invention, and for that reason has not been illustrated or described.

50 The holes 12 are drilled equal distance apart and provided with a key seat 13, and so arranged that the blades may be arranged in spiral or staggered position on the shaft.

Each blade 14 is provided with a shank 55 15 formed cylindrical and provided with a key seat 16. The blade 14 is considerably wider than the diameter of the shank, the shank being so placed that a shoulder 17 is provided to the rear side of it, when in position in the said shaft. The shoulder 17 terminates in a flange 18 which is designed to fit the shaft when in position.

The back edge of the blade is substantially parallel with the longitudinal center line of the shank 15 while the front edge is preferably slanted ahead so that the outer end of the blade is wider than the inner end. The outer edge 19 is formed circular and provided at each side with a rib 20. 70 The forward end of the edge 19 is provided with a pointed portion 21 which greatly assists in breaking up the larger chunks of material to be granulated. A blade is provided for each of the holes 12 and is placed 75 in position with the shank 15, secured therein by means of a key 22 and with the shoulder 17 adjacent to the shaft. The trough 10 is generally filled about three fourths full of material to be granulated. The shaft is 80 then rotated in a clock-wise direction, as shown in Fig. 1, the points 21 will split up the large chunks while the forward edge will cut and break the material into smaller chunks, and in granulation it will be seen 85 that the forward edge of the blade 14 will wear away, also the point 21. But to prevent the said point 21 from wearing off and from becoming round, I have provided the ribs 19, the blade portion 14 is comparatively thin and will wear faster than the thick heavy portion formed by the ribs 19, then it will be seen that instead of the forward and outer corner becoming rounded it will have a tendency to become more pointed 95 by being used.

The shoulder 17 forms a brace against the backward movement of the blade 14 helping to strengthen the shank 15, the flange 18 helps to brace the blade from a lateral movement.

The holes 12 are drilled through the shaft so that the shank may be driven out by placing a punch through the opposite end of the hole.

Thus it will be seen that I have provided a granulator blade so constructed as to strengthen it and also provide means where-

by the point will stay sharpened when used.

Having thus described my invention, I claim:

1. A granulator blade comprising a body portion and a shank, said body portion having curved side ribs at its inner and outer ends, the outer ribs being eccentric to the inner ribs and having front cutting edges in line with the outer end of the body portion, said shank being intermediate of the front and rear edges of the said body portion.

2. A granulator blade comprising a body portion and a shank, said body portion having curved side ribs at its inner and outer ends, and having its front edge sharpened, the said sharpened edge being ahead of the front edge of said body portion, and said shank being intermediate of the front and rear edges of said body portion.

3. A radial granulator blade, for a rotary shaft, having a radial shank, a shoulder adjacent to the rear side of said shank and lateral ribs at its peripherical edge.

4. In a device of the class described, a rotary shaft, having a series of radial open-

ings, a radial blade for each of the said openings, having a shank, and lateral ribs at its peripherical edge.

5. In a device of the class described, a rotary shaft, having a series of radial openings, a radial blade for each of said openings, having a shank, and lateral ribs at its peripherical edge, and means for locking said shanks in said openings.

6. In a device of the class described, a rotary shaft, having a series of radial openings, a radial blade for each of said openings, having a shank, and lateral ribs at its peripherical edge, and a shoulder designed to rest on the shaft adjacent to the rear side of the said shank.

7. In a device of the class described, a rotary shaft, having a series of radial openings, a radial blade for each of said openings, having a shank, and lateral ribs at its peripherical edge, a shoulder designed to rest on the shaft adjacent to the rear side of the shank, and means for locking said shank in said shaft.

HALVER R. STRAIGHT.
